Primary Examiner — Lauren R Calve(74) *Attorney, Agent, or Firm* — Westerman, Hattori, Daniels & Adrian, LLP(57) **CLAIM**

The ornamental design for a door handle for an automobile, as shown and described herein.

DESCRIPTION

FIG. 1 is a front side perspective view of a door handle for an automobile;

FIG. 2 is a front view thereof;

FIG. 3 is a left side view thereof;

FIG. 4 is a right side view thereof;

FIG. 5 is a top plan view thereof; and,

FIG. 6 is a bottom view thereof.

The broken lines in the drawings illustrate portions of the door handle for an automobile that form no part of the claimed design.
